CRANKSHAFT GRINDING MACHINE

Wallace H. Wood, Worcester, Mass., assignor to
 Norton Company, Worcester, Mass., a corpora-
 tion of Massachusetts

Application November 18, 1937, Serial No. 175,295

5 Claims. (Cl. 51—72)

This invention relates to grinding machines, and more particularly to a machine for grinding the bearings of a crankshaft.

One object of the invention is to provide a simple, thoroughly practical grinding machine in which a manually operable control lever serves to control a hydraulic wheel feeding mechanism and an electrical drive for the work piece. Another object of the invention is to provide a control mechanism for a grinding machine in which a single lever is operatively connected so that when moved in one direction, it serves to control a hydraulic wheel feeding mechanism and when moved in the other direction serves to control stopping and starting of the work rotation. A further object of the invention is to provide an electrical control apparatus for a grinding machine in which an electrical control apparatus including a manually operable push button serves to cause a reverse feeding movement of the grinding wheel and a stopping of the work rotation thereafter.

This invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a front elevation of the improved crankshaft bearing grinding machine;

Fig. 2 is a transverse sectional view taken approximately on the line 2—2 of Fig. 1, on an enlarged scale, showing the wheel slide and the drive for the grinding wheel in elevation;

Fig. 3 illustrates a sectional view through the control lever mechanism combined with an electrical wiring diagram showing the control for the work driving motor and the solenoid for electrically reversing the wheel feed motor;

Fig. 4 is a fragmentary cross-sectional view, on an enlarged scale, taken approximately on the line 4—4 of Fig. 1, showing the control lever mechanism and its operating parts;

Fig. 5 is a fragmentary sectional view, on an enlarged scale, of the lower part of Fig. 4;

Fig. 6 is a fragmentary horizontal sectional view, taken approximately on the line 6—6 of Fig. 5, of the latch mechanism for controlling the work rotation; and

Fig. 7 is a diagrammatic view showing the various operating positions of the control lever.

As illustrated in the drawings, the machine

embodimenting this invention comprises a base 10 which supports a longitudinally reciprocable work supporting table 11 on the usual V-way 12 and flat way 13 for a longitudinal reciprocating movement relative to the base 10. A motor driven headstock 14 and a footstock 15 are adjustably mounted on the swivel table 26 clamped on the table 11 and are arranged rotatably to support a work piece, such as a crankshaft 16, on a headstock center 17 and a footstock center 18 in operative relation with a rotatable grinding wheel 19.

The grinding wheel 19 is rotatably supported on a wheel slide 20 of the usual type, such as shown in my prior U. S. Patent No. 2,071,677 dated February 23, 1937. The grinding wheel 19 may be rotated by an electric motor 21 mounted on the wheel slide 20. The motor 21 is provided with a pulley 22 which is connected by a multiple V-belt 23 with a pulley 24 on the end of a wheel spindle 25.

A fluid pressure mechanism is provided to reciprocate the work table 11. In the form illustrated, a cylinder 30 is fixedly mounted to the under side of the table 11. The details of the table traverse mechanism have not been shown in detail since they are not considered to be an essential part of the present invention. For further details of construction as to the hydraulic table traverse mechanism, reference may be had to my prior U. S. Patent No. 2,071,677 dated February 23, 1937.

A hollow box-like sump or reservoir 35 is formed in the base 10 and serves as a fluid reservoir for the pressure system. Fluid is drawn from the reservoir 35 through a pipe 36, by a motor driven pump 37, and is forced through a pipe 38 and a pipe 39 to a table control valve 40. A pressure relief valve 41 is provided in the pipe 38 and is arranged to allow fluid under pressure to by-pass through a pipe 42 and return to the reservoir 35 in case the pressure within the system increases above a desired pressure.

The control valve 40 comprises a reversing valve and a speed control or throttle valve, the details of which will not be described since reference may be had to my prior patent above referred to for details of valve construction.

A reversing lever 50 is fixedly mounted on a pivotally mounted shaft 51 on the front of the machine base 10. The reversing lever 50 is arranged to be actuated by a pair of adjustable table dogs 52 and 53 which are adjustably supported in a T-slot 54 on the front edge of the table 11. The reversing lever 50 is operatively

connected to actuate the reversing valve in the control valve 40 to reverse the direction of movement of the table 11.

A second control lever 60 is pivotally mounted 5 on a stud 61 on the front of the machine base 10.

The lever 60 is operatively connected to the control valve 40 and is arranged when moved toward or from the machine base 10 to stop or start the hydraulic traversing movement of the table 11.

10 A speed control knob 62 which moves with the lever 60 is operatively connected to regulate a speed control or throttle valve contained within the valve 40 so as to control the table speed. The details of the valve 40 and the connection of the control levers 50 and 60 therewith have not been 15 illustrated, since this mechanism is identical with that shown in my prior United States Patent No. 2,071,677, to which reference may be had for details of disclosure not contained herein.

20 A wheel feeding mechanism is provided for manually feeding the grinding wheel 19 toward and from the work 16, which comprises a half nut 65 depending from the wheel slide 20. The half nut 65 meshes with a rotatable cross feed screw 66 which is slidably keyed to a rotatable sleeve 67. The rotatable sleeve 67 is supported in a bearing 68 in the base 10 and carries at its other end a gear 69. The gear 69 meshes with a pinion 70 formed on the inner end of a rotatable shaft 71 which is journaled in bearings 72 and 73, respectively, in the base 10. A manually operable feed wheel 75 is mounted on the forward end of a stud 76. The feed wheel 75 carries a pinion 77 which meshes with a gear 78 rotatably supported on a stud 79. A gear 80 is formed integral with gear 78 and meshes with a gear 81 keyed on the outer end of the shaft 71, so that a manual rotation of the feed wheel 75 serves to rotate the feed screw 66 in either direction to cause a forward or rearward feeding movement of the grinding wheel 19 and the wheel slide 20.

40 The feed wheel 75 may be provided with the usual well known micrometer adjusting mechanism 82 which is substantially identical with that shown in the expired U. S. patent to Norton No. 762,838 dated June 14, 1904. This micrometer mechanism serves precisely to adjust the stop on the manual infeed to permit a compensation for wheel wear.

50 In the preferred construction, the wheel slide 20 is arranged so that it may be moved toward and from the work piece 16 to grind the same to a predetermined size by means of a fluid pressure actuated feeding mechanism which may be 55 of the type shown in my prior Patent No. 2,082,728. As illustrated, the rear end of the feed screw 66 is rotatably supported in a slidably keyed bearing 88 which is supported in a casing 86 on the base 10 of the machine. A fluid pressure cylinder 87 is attached to the casing 86 and contains a slidably mounted piston 88 which is connected by a piston rod 89 with the bearing member 85 and is arranged so that when fluid is admitted under pressure to a cylinder chamber 60 90, the piston 88 will be moved into its rearward position (Fig. 2), transmitting a corresponding movement through the feed screw 66, the half nut 65, to move the wheel slide 20 and the grinding wheel 19 rearwardly to an inoperative position.

70 Similarly, when fluid under pressure is admitted to a cylinder chamber 91, the wheel slide 20 and grinding wheel 19 are caused to move in a forward direction to move the grinding wheel

toward the crankshaft 16 for a grinding operation. When fluid is admitted either to the cylinder chamber 90 or the cylinder chamber 91, a rapid approaching or receding movement of the wheel 19 and wheel slide 20 is provided.

75 It is desirable to provide a suitable fluid pressure controlling or feed regulating mechanism for modifying the rapid approaching movement caused by the piston 88 to obtain a controlled and predetermined feeding movement of 10 the grinding wheel 19. In the preferred construction, a self-contained dash pot feed regulator is provided comprising a pair of dash pot cylinders 92, 93 which contain dash pot pistons 94 and 95, respectively. The dash pot pistons 15 94 and 95 and their respective cylinders 92 and 93 are arranged with their axes parallel to each other and spaced on diametrically opposite sides of the piston rod 89. The dash pot pistons 94 and 95 are normally held in a rearward position 20 by means of springs. Adjustable stop screws 96 and 97 serve, respectively, to limit the rearward movement of the dash pot pistons 94 and 95.

25 The forward rapid feeding movement of the grinding wheel 19 and the wheel slide 20 continues until an adjustable sleeve 98, which is adjustably supported on the rear portion of the piston rod 89, engages the ends of the dash pot pistons 94 and 95, respectively, after which the rapid approaching movement of the grinding 30 wheel 19 and the wheel slide 20, as produced by the piston 88, is reduced to a slower predetermined grinding feed due to the fact that fluid confined within the dash pot cylinders 92 and 93, which are interconnected, exhausts through a 35 passage 99, a needle valve 100, into a reservoir 101 contained within the dash pot casing. By adjusting the aperture of the needle valve 100, a desired and predetermined infeed may be obtained.

40 When fluid under pressure is admitted to the cylinder chamber 90 to cause a rearward movement of the piston 88, the sleeve 98 moves rearwardly and the released compression of the springs within the dash pot cylinders 92 and 93 45 serves to return the dash pot pistons 94 and 95, respectively, to the rearward position, as illustrated in Fig. 2. During the rearward movement of the dash pot pistons 94 and 95, a suction is created within the dash pot cylinder chambers 50 92 and 93, respectively, which serves to aid in drawing fluid from the reservoir 101, through a pipe 102, and a ball check valve 103, to fill the dash pot cylinder chambers 92 and 93 for the next infeeding operation. During the infeeding 55 movement of the dash pot pistons 94 and 95, fluid within the dash pot cylinders 92 and 93 serves to hold the ball check valve 103 closed so that fluid within the dash pot cylinder chambers 92 and 93 is forced out through the passage 99 60 and needle valve 100, into the reservoir 101 to produce the desired infeeding movement of the grinding wheel.

65 A fluid pressure system is provided for conveying fluid under pressure to the cylinder 87. An independent system may be provided, if desired, but for the sake of simplicity of illustration, the fluid under pressure from the pump 37 is utilized to operate the wheel feeding mechanism. Fluid under pressure from the pump 37 70 is forced through the pipe 38 and a pipe 104, to a control valve 105. The control valve 105 is of a balanced piston type comprising a valve stem 106 having formed integral therewith valve pistons 107, 108, 109 and 110.

In the position of parts as illustrated, the valve stem 106 is in its rearward position so that fluid under pressure passing through the pipe 104 enters a valve chamber between the valve pistons 108 and 109 and passes through a passage 111 into cylinder chamber 90, to move the piston 88 rearwardly to withdraw the wheel slide 20 and the grinding wheel 19 from operative engagement with the crankshaft 16. During this movement, fluid is exhausted from the cylinder chamber 91, through a passage 112, through a valve chamber located between the valve pistons 107 and 108, and through a pipe 113 which exhausts into the reservoir 35.

15 The valve stem 106 is shifted into the reverse position, that is, it is moved forward or toward the left (Fig. 2), so that fluid under pressure passing through the pipe 104 and the valve chamber between the valve pistons 108 and 109 passes 20 through the passage 112 into the cylinder chamber 91 to cause a forward feeding movement of the piston 88, the wheel slide 20 and the grinding wheel 19.

25 During the forward feeding movement, fluid is exhausted from the cylinder chamber 90, through the passage 111, into a valve chamber between the valve pistons 109 and 110, respectively, and out through the pipe 113 into the reservoir 35.

30 The infeeding movement of the grinding wheel 19 under the control of the piston 88 continues at a rapid rate until the sleeve 98 picks up the dash pot pistons 94 and 95 to reduce the approaching movement of the grinding wheel 19 to a slow 35 predetermined grinding feed which continues until an adjustable stop sleeve 115, which is in turn supported on the piston rod 89, engages a stop surface 116 on the end of the dash pot casing, thereby positively limiting or stopping the forward advancing movement of the wheel slide 20 and the grinding wheel 19. The sleeves 98 and 115 are both adjustably mounted, the sleeve 98 being threaded upon the outer extending end of the piston rod 89 and being held in adjusted position thereon by means of a lock nut. The stop sleeve 115 is mounted on the periphery of the sleeve 98 and is arranged to be locked in adjusted position thereon by lock nuts.

35 The headstock 14 is preferably a motor driven headstock in which an electric motor 120 is mounted on the upper part of the headstock. The motor 120 is provided with a pulley 121 which is connected by a V-belt 122 with a pulley 123 mounted on the end of a rotatable shaft 124. The shaft 124 is operatively connected to rotate a face plate 125 which in turn drives the crankshaft 16. The headstock 14 and its drive have not been illustrated in detail since they are not considered to be part of the present invention. 40 The headstock 14 is substantially identical to the headstock shown in the U. S. patent to Belden No. 1,631,458 dated June 7, 1927, to which reference may be had for a more detailed disclosure of the driving mechanism for the headstock. The face plate 125 carries the usual driving pin which engages an aperture or recess in the end of the crankshaft or work piece 16 being ground to rotate the same.

45 The crankshaft or other similar work piece 16 to be ground is of considerable weight and to facilitate operation of the machine and obtain the maximum production therefrom, it is desirable to provide a suitable mechanism for abruptly stopping the rotation of the face plate 125 of the headstock 14 and work piece after the grind-

ing operation has been completed. In the preferred form of construction, the headstock motor 120 is of the reversible type which is controlled by a magnetic reverse starter switch 128, and a motor brake switch 127 is mounted on top of the 5 motor 120. In the electrical diagram (Fig. 3), the electric motor 120 is provided with two fields which are controlled by the magnetic starter reverse switch 128 which throws the forward end field of the motor 120 into operation. When a 10 control lever to be hereinafter described is shifted to stop the work rotation at the end of a grinding operation, a normally open limit switch 129 is closed by movement of a control lever, which serves to complete the circuit in the power 15 lines through the motor brake switch 127 and through the starter reverse switch 128 which serves to actuate a magnetic reverse starter switch 130 which serves instantaneously to reverse the 20 current in the motor 120 and thereby instantaneously to stop the rotation of the motor 120 and the headstock face plate 125, thus reducing the idle time during the finish grinding of one piece of work 16 and the starting of grinding of the next.

25 The table 11 may be traversed longitudinally by means of a manually operable traverse mechanism comprising a hand wheel 135 which is mounted on the outer end of a rotatable shaft 136. The shaft 136 carries at its inner end a gear 137 which meshes with a gear 138. The gear 138 is rotatably supported on a shaft or stud 139. A gear 140 is also rotatably mounted on the shaft 139 and is fixedly connected to rotate with the gear 138. The gear 140 meshes with a gear 141 mounted on the outer end of a rotatable shaft 142. The inner end of the shaft 142 carries a pinion 143 which meshes with a rack bar 144 depending from the under side of the table 11. It will be readily apparent from this disclosure that rotation of the hand wheel 135 will transmit a longitudinal traversing movement to the table 11 to position the crankshaft 16 relative to the grinding wheels 19. The hand wheel 135 and the gear mechanism above described are 40 preferably arranged so that the upper part of the hand wheel 135 is moved in a direction it is desired to traverse the table 11 so as to facilitate operation of the machine.

45 In a crankshaft grinding operation, such as that disclosed in this application, for grinding the bearings of the shaft 16, it is desirable to provide an interlocked relationship between the work rotation and the wheel feed so that after the grinding operation has been completed, the wheel slide 20 must be withdrawn so that the grinding wheel 19 is out of contact with the finish ground portion of the work piece 16 before the work rotation may be stopped. This is preferably accomplished by providing a manually operable control lever 145 which is arranged so that it may control both the work rotation and the infeeding movement of the grinding wheel 19. The control lever 145 is supported within a casing 146. The lever 145 is preferably mounted in a gimbal joint so that it is free to be moved in any direction. As illustrated in Fig. 3, the lever 145 is pivotally supported on a stud 147. The stud 147 is supported by a ring-shaped member 148. The ring-shaped member 148 is in turn supported 55 by the opposed studs 149 and 150 which are supported in the casing 146.

60 It will be readily apparent from the disclosure in the upper portion of Fig. 3 that the lever 145 may not only be moved about the axis of the 65

stud 147 but may also be moved about the axis of the studs 149 and 150 or may be moved in a combined path, thus forming a universal joint support for the lever 145. The lever 145 is provided with a downwardly extending arm 151 which has an outwardly projecting lug 152 arranged to engage a slidably mounted pin 153 which is in turn arranged to actuate a control lever 154 on the limit switch 129. The limit switch 129 is normally held in an open position by means of a spring 155 which holds the lever 154 in engagement with a stop 156. When the control lever 145 is moved in a counterclockwise direction (Fig. 3), the lug 152 engages the pin 153 and moves it toward the right. This movement serves to rock the control lever 154 of the limit switch 129 to close the circuit. The closing of the limit switch 129 operates in a manner above described to start the rotation of the work drive motor 120.

In order to interlock the work rotation control with the wheel feed mechanism, a downwardly projecting lever 157 is formed integral with the ring-shaped member 148. The lever 157 is connected at its lower end by a stud 158 with a link 159. The other end of the link 159 is connected by a stud 160 with a rock arm 161 pivotally supported on a stud 162 which is in turn supported on an upwardly projecting bracket 163. The upper end of the rock arm 161 is provided with an elongated slot 164 within which a pin 165 may slide. The pin 165 is fixedly mounted on the downwardly projecting lug fixedly fastened to the valve stem 106. When the control lever 145 is moved away from the operator into the position illustrated in Fig. 2, this motion will be transmitted through the link 159, the rock arm 161, to move the valve stem 106 toward the right (Fig. 2) to position the valve pistons, as illustrated in Fig. 2, so as to admit fluid under pressure through the control valve 105 to the cylinder chamber 90 to cause a rearward movement of the grinding wheel 19. Similarly, when the control lever 145 is moved toward the operator (Fig. 2), this motion will be transmitted through the link 159, the rock arm 161, to move the valve stem 106 toward the left (Fig. 2) to shift the valve pistons so that fluid under pressure passing through the control valve 105 will be admitted through passage 112 into the cylinder chamber 91 to cause a forward approaching movement of the grinding wheel 19.

In order to interlock the work rotation with the wheel feeding mechanism so that the work rotation cannot be stopped until the grinding wheel 19 has moved rearwardly out of contact with the work piece 16 being ground, a suitable latch mechanism is provided comprising a stud 166 which depends from the lower surface of the lever 151. A pivotally mounted latch member 167 supported on a stud 168 is normally held in the full line position (Fig. 5) by means of a spring 169 which tends to rock the latch member 167 in a clockwise direction so that the short arm 170 engages a stop screw 171 adjustably mounted within the casing 146. When the lever 145 is in the position illustrated in Fig. 4, it may be swung in a direction parallel with the table 11 without affecting the latch mechanism. When the lever 145 is moved in a clockwise direction (Fig. 4), the lower arm 151 which carries the stud 166 moves into position 151a and the stud into position 166a, thereby depressing the latch 167 into the dotted line position 167a (Fig. 5). In this position of the parts, when the lever 145 is moved

parallel to the table 11, the pin 166 rides across the upper face of the spring-pressed latch 167 until the pin 166 passes over the edge of the latch 167 into position 166b (Fig. 6) whereupon the released compression of the spring 169 returns the latch 167 from position 167a into the full line position, thus locking the lever 145 in dotted line position 145a (Fig. 3) and holding the limit switch 129 closed. This latch permits the lever 145 to be moved toward and from the operator to cause an approaching or receding movement of the grinding wheel 19, but prevents a movement of the lever 145 longitudinally of the machine to stop the work rotation when the grinding wheel 19 is in its forward grinding position.

The operating positions of the lever 145 are shown diagrammatically in Fig. 7. When the lever 145 is in the position 145c, the work rotation is stopped and the wheel slide 20 is in its rearward position to permit unloading the finish ground work piece 16 and inserting a new work piece there instead. When the lever 145 is shifted from position 145c into position 145d, this transmits a movement through the link 159 and rock arm 161 to shift the valve stem 106 so as to cause the grinding wheel 19 to move forward toward the work piece 16. During this forward approaching movement of the grinding wheel 19, the work rotation is preferably stopped so that the operator may readily observe the position of the grinding wheel 19 relative to the portion of the work 16 to be ground and, if necessary, longitudinally move the table 11 by means of the hand wheel 135 to bring the work piece 16 into the desired relationship with the grinding wheel 19 before starting the rotation of the work piece 16. After the work piece 16 has been located as desired, the control lever 145 may then be shifted into position 145a (Fig. 7) which serves to close the limit switch 129 and thereby start the rotation of the work piece 16.

In the work rotating position 145a (Fig. 7), the latch pin 166 is in a latched position 166b (Fig. 6). In this position of the parts, the control lever 145 cannot be shifted from position 145a into position 145d since the latch pin 166 rides on the side of the latch 167 and prevents such movement. The only direction in which the lever 145 may be moved is in a direction toward position 145b (Fig. 7) which serves through the connecting link 159 and rock arm 161 to shift the valve stem 106 and the control valve 105 into the full line position as shown in Fig. 2 to start a rearward movement of the grinding wheel 19. When the lever 145 has been moved toward position 145b through a sufficient extent so that latch pin 166 swings so that it clears the inclined portion of the latch 167, the released compression of a spring 172 serves to rock the lever 145 in a clockwise direction (Fig. 3) so that the lever 145 assumes the full line position illustrated in Fig. 3.

It will be apparent from the foregoing disclosure that in starting a grinding operation on a portion of the crankshaft 16 to be ground, either the work 16 or the grinding wheel 19 may be moved first, as desired, but that in stopping the machine, it is necessary first to shift the control lever 145 to withdraw the grinding wheel 19 from operative contact with the work 16 before the work rotation can be stopped, thus preventing the grinding of a flat on the surface of the work 16 being ground.

It is desirable to provide a safety control whereby the grinding wheel 19 may be started in a

rearward movement and the work rotation automatically stopped in case the machine fails to function properly. This is preferably accomplished by means of an electrically operated control mechanism comprising a normally open push button 175 which is located on the front of the machine within easy reach of the operator. The push button 175 is normally open and is connected in series with a solenoid 176 which is preferably of the push type. Armature 177 of the solenoid 176 is connected by a stud with an outwardly extending projection of the valve stem 106. If it is desired quickly to stop the grinding cycle, the operator presses the button 175 to close the circuit and energize the solenoid 176 which pushes the valve stem 106 toward the right (Fig. 2) into the full line position shown which serves to admit fluid under pressure to the cylinder chamber 98 and thereby initiate a rearward movement of the grinding wheel 19. The movement of the valve stem 106 toward the right (Fig. 2) by the solenoid 176 serves to rock the lever 161 in a clockwise direction and at the same time shifts the link 159 toward the left (Fig. 2) so that the latch pin 166 swings from position 166b into the position 166c (Fig. 5) whereupon the released compression of the spring 172 serves to rock the lever 145 in a clockwise direction (Fig. 3), thus withdrawing the lug 152 on the arm 30 151 and allowing the released tension of the spring 155 to open the limit switch 129 and thereby stop the rotation of the work drive motor 120.

The operation of this mechanism will be readily apparent from the foregoing disclosure. A work piece, such as a crankshaft 16, is mounted on the machine on headstock center 17 and footstock center 18. The table 11 is then traversed longitudinally either by the fluid pressure mechanism 40 above described or manually by rotation of the hand wheel 135 to position the crankshaft 16 relative to the grinding wheel 19. The control lever 145 is then preferably shifted from position 145c into the position 145d to cause a forward 45 approaching movement of the grinding wheel 19 while the work 16 is stationary, thus permitting the operator to observe the relative position of the crankshaft 16 to the operative face of the grinding wheel 19 and, if necessary, permitting a 50 manual adjustment of the table 11 before the grinding wheel 19 reaches a grinding position. After the operator is satisfied that the crankshaft is properly located relative to the wheel 19, the lever 145 may be shifted from position 145d 55 into position 145a, which serves to close the limit switch 129 and thereby start the rotation of the crankshaft 16 for a grinding operation. The grinding operation continues until the portion of the shaft 16 has been ground to a predetermined 60 size, either determined by a positive stop surface 116 above described or by the usual well known dial indicator.

In the grinding of a portion of the crankshaft to the desired predetermined size, the manually operable feeding mechanism may be utilized, if desired, or in the preferred form of operation of the machine the power operated, hydraulically driven mechanism may be utilized to feed the grinding wheels to grind the work to a predetermined size. The machine may be equipped with the well known dial indicator (not shown) suspended from a portion of the machine so that the operator may visibly watch the reduction in size of the work piece. When the dial indicator indicates that the work has been ground to the re-

quired size, the push button 175 is actuated, which operates in the manner above described first to cause a separating movement of the grinding wheel relative to the portion of the crankshaft 16 being ground, and then a stopping of the work rotation after the grinding wheel 19 has receded from engagement with the portion of the crankshaft being ground. The push button 175 also serves in case of emergency quickly to stop the grinding operation by returning the wheels to their rearward position and stopping the rotation of the crankshaft.

If desired, the receding movement of the grinding wheel 19 and the stopping of the rotation of the crankshaft 16 may be controlled by the manually operable control lever 145. The control lever 145 is shifted manually from position 145a to position 145b which serves to start the rearward movement of the grinding wheel 19 to separate the wheel from the work while the work is 20 rotating. When the lever 145 is in position 145b, so that the latch pin 166 is in position 166c (Fig. 5) out of engagement with the side face of the latch 167, the lever 145 may then be shifted manually or automatically under the released compression of the spring 172 into position 145c 25 to stop the work rotation so as to facilitate removal of the finish ground crankshaft 16 and the loading of a new crankshaft in the machine.

It will thus be seen that there has been provided by this invention apparatus in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawings is to be interpreted as illustrative and not in a limiting sense.

I claim:

1. In a crankshaft grinding machine, a transversely movable rotatable grinding wheel, means including a fluid pressure piston and cylinder to move said wheel transversely in either direction, a control valve to control the admission of fluid to said cylinder, a rotatable work support including a headstock and a footstock, means including an electric motor to drive said headstock, a switch to start said motor, a main control lever which is operatively connected when moved in one direction to actuate said switch to rotate said headstock and when moved in a second direction to actuate said control valve to cause a forward or rearward movement of the grinding wheel, and means including a latch to hold said lever in a position to maintain said switch closed during the infeeding movement of the grinding wheel, said parts being arranged to prevent stopping of said motor except when said wheel has moved rearwardly out of operative engagement with the work piece.

2. In a crankshaft grinding machine, a transversely movable rotatable grinding wheel, means including a fluid pressure piston and cylinder to move said wheel transversely in either direction, a control valve operatively connected with said cylinder and arranged to control the admission and exhaust of fluid therefrom, means including a solenoid to actuate said valve to cause a rearward movement of the grinding wheel, a rotatable work support including a headstock and a footstock, means including an elec-

- tric motor to drive said headstock, a main control lever which is operatively connected to actuate said switch when moved in one direction to stop or start said motor and to shift said control valve to cause either a forward or rearward movement of the grinding wheel when moved in another direction, and means including a latch associated with said lever and arranged to hold said lever against movement in one direction during the grinding operation to prevent stopping said headstock except when the grinding wheel is moved rearwardly out of engagement with the crankshaft.
3. In a crankshaft grinding machine, a transversely movable rotatable grinding wheel, means including a fluid pressure piston and cylinder to move said wheel transversely toward and from a crankshaft to be ground, a rotatable work support including a motor driven headstock and a footstock, means including an electric switch to control said motor, a pivotally mounted main control lever, operative connections between said lever and switch whereby movement of said lever in one direction serves to actuate said switch to control rotation of said work support, operative connections between said lever and control valve whereby the valve is shifted to cause either a forward or rearward feeding movement of the grinding wheel when the lever is moved in a second direction, and means including a latch mechanism which is arranged to hold the control lever to maintain said switch in a closed position during the grinding operation, said latch being arranged to permit free movement of the control lever in a direction to control the movement of the grinding wheel.
4. In a crankshaft grinding machine, a transversely movable rotatable grinding wheel, means including a fluid pressure piston and cylinder to move said wheel transversely toward and from a crankshaft to be ground, a control valve therefor, a solenoid to actuate said valve in one direction, a rotatable work support including a motor driven headstock and a footstock, means including an electric switch to control said motor, a pivotally mounted main control lever, operative connections between said lever and switch whereby movement of said lever in one direction serves to actuate said switch to control rotation of said work support, operative connections between said lever and control valve whereby the valve is shifted to cause either a forward or rearward feeding movement of the grinding wheel when the lever is moved in a second direction, and means including a latch mechanism which is arranged to hold the control lever to maintain said switch in a closed position during the grinding operation, said latch being arranged to permit free movement of the control lever in a direction to control the movement of the grinding wheel.
5. In a crankshaft grinding machine, a transversely movable rotatable grinding wheel, means including a fluid pressure piston and cylinder to move said wheel transversely in either direction, a control valve therefor, means including a solenoid to actuate said valve so as to cause a rearward movement of the grinding wheel, a rotatable work support including a motor driven headstock and a footstock, means including an electric switch to control said headstock motor, a pivotally mounted main control lever, operative connections between said motor and said switch whereby the headstock motor is started or stopped when the lever is moved in one direction, a spring normally to hold said lever in position so that the headstock motor is stopped, connections between said control lever and said valve whereby the grinding wheel is caused to move either in a forward direction or rearward direction, means including a latch associated with said lever and arranged to hold said switch closed to rotate the work during the grinding operation, and means including a push button which is operatively connected to energize said solenoid so as to shift the valve and cause a rearward movement of the grinding wheel, said parts being arranged so that when the grinding wheel has receded in a rearward direction to a predetermined extent, the latch automatically releases the control lever and the released compression of a spring serves automatically to shift said lever and open said switch to stop the work rotation.

WALLACE H. WOOD.
